KEYBOARD ENCODER

Edward E. Salter, Fairport, and Hugh M. Lee, Rochester, N.Y., assignors to The Singer Company, a corporation of New Jersey

Filed Mar. 3, 1969, Ser. No. 15,983

Term of patent 14 years

Int. Cl. D14—02

U.S. Cl. D26—5

FIG. 1 is a front perspective view of a keyboard encoder embodying our new design;

FIG. 2 is a top plan view thereof; and

FIG. 3 is a rear perspective view thereof.

The broken line showing of indicia in FIGS. 1 and 2 is for purposes of illustration only.

What is claimed is:

The ornamental design for a keyboard encoder, substantially as shown and described.
